UNITED STATES PATENT OFFICE.

FRED R. COATS AND JEAN F. HARTWELL, OF SPRINGFIELD, ILLINOIS.

WATCH.

1,333,161.

Specification of Letters Patent.

Patented Mar. 9, 1920.

Application filed June 4, 1919. Serial No. 301,650.

To all whom it may concern:

Be it known that we, the undersigned, FRED R. COATS and JEAN F. HARTWELL, citizens of the United States, residing at 5 Springfield, in the county of Sangamon and State of Illinois, are joint inventors of the Improvement in Watches, of which the following is a specification.

The invention relates to watches, and is primarily designed for watches from "0" 10 to "10/0" sizes inclusive, American standard, or for small watches known in the art as ten and a half line watches, or the like. In general practice the barrel of large size 15 or standard watches is proportional to, or has a direct ratio to the diameter of the watch, but in small size watches varying in size from seven lines to fourteen lines, as hitherto constructed, the restricted available 20 space does not admit of the use of a barrel in the standard ratio to the diameter of the watch.

Prime purposes of the invention are to provide watch mechanism constructed and 25 arranged to permit the use in a small size watch of a relatively larger barrel for the main spring than has hitherto been used; thus closely approximating in small watches, the barrel of standard proportions, hitherto 30 used in larger or standard size watches and thereby greatly increasing the scope and effectiveness of the spring of the small size 35 watch; to provide a watch movement embodying in conjunction with an enlarged barrel, a horizontal or cylinder escapement, as distinguished from a lever escapement; thus dispensing with the center wheel and pinion, and the pallet arbor and appurtenances.

Secondary purposes of the invention are: to provide a regulator of improved construction; to provide a dial plate of improved construction easily and quickly attachable to or removable from the top plate without 45 detaching the hands, and to provide in conjunction with the dial plate, an hour hand, a minute hand, and a second hand removable with the dial plate without the necessity for detaching the hands from the second hand 50 pinion, the cannon pinion and the hour wheel; to provide means for accurate adjustment of the cylinder staff; and to provide other improved details of construction as will hereinafter appear.

The invention is illustrated in the annexed drawings, to which reference is hereby made, and will now be fully described and

the novel features thereof will be recited in the claims.

Figure 1 is a top plan of a watch embodying the invention; 60

Fig. 2 is an enlarged inverted sectional view taken on the line X. X. of Fig. 1, showing details of the dial plate, and connected parts; 65

Fig. 3 is an enlarged inverted fragmentary sectional view through the pillar plate, dial plate, and adjacent parts, taken on the line Y. Y. of Fig. 1;

Fig. 4 is an enlarged view showing details 70 of the regulator;

Fig. 5 is an enlarged fragmentary plan showing means for adjusting the position of the cylinder relative to the escape wheel;

Fig. 6 is an enlarged inverted fragmentary sectional view showing details of the 75 balance cock and appurtenances;

Fig. 7 is a diagram showing the relatively increased diameter of barrel gained by omitting the center wheel and the center pinion 80 hitherto used in watches having cylinder-escapements; also showing the increased diameter of balance wheel, and the relative simplicity of construction gained by omitting the lever escapement, comprising numerous parts hitherto used in small watches, 85 varying in size from seven lines to fourteen lines;

Fig. 8 is a diagrammatic top-plate-view, 90 showing the old dial train, in which the barrel-gear actuates the center pinion, and the cannon pinion, staked on the center-pinion-staff, drives the minute wheel; in comparison with the improved train, in which the barrel carries a compound gear which drives 95 the cannon pinion and also drives the hour wheel. In this view the arrangement of old parts is indicated by broken and dotted lines; and the arrangement of new parts is indicated by full lines. 100

Fig. 9 is a diagram, partly in section, showing the connection of the compound gear with the barrel.

Fig. 10 is a diagram, on a reduced scale, 105 showing a plan of the flat blank from which the dial plate is formed.

Fig. 11 is a diagram of an old train, illustrating the absorption of power between the barrel and the escape wheel pinion; and

Fig. 12 is a similar diagram of our improved train. 110

The same reference numerals designate the same parts in all the views.

The several parts of the improved mecha-

nism, and some parts used in prior mechanisms (marked "old") but not used in the improved mechanism are briefly enumerated in the following notation:

Notation.

1. Pillar plate.	10	dating the dowel pins 64 on the boss 62.
1 ^a . Top plate.		75
2. Ratchet wheel.		75
3. Ratchet wheel washer.		75
4. Ratchet wheel screw.		75
5. Winding wheel.		75
6. Winding wheel washer.		75
7. Winding wheel screw.		75
8. Balance cock.	15	77. Elongated hub of the hour wheel 33. 80
9. Scape wheel bridge.		78. Central opening in the dial plate accommo- dating the hub 77.
10. Balance wheel.		79. Elongated hub of the cannon pinion.
11. Hair spring stud on the balance cock.	20	80. Circumferential rim of the pillar plate.
12. Hair spring stud on the balance cock.		81. Notches in the rim of the pillar plate.
13. Regulator as a whole.		82. Lines indicating the bend of the snaps.
14. Hair spring.	25	83. Necks of the snaps.
16. Escape wheel.		84. Recess in the pillar plate accommodat- 90 ing the adjusting screw 68 (Fig. 5).
17. Third wheel.		85. Circle representing the old pillar plate (Fig. 7).
18. Arm on the regulator.		86. Center pinion (old).
19. Regulator pins.		87. The barrel-gear (old). 95
20. 2nd wheel pinion.		88. The barrel-gear, new.
21. 3rd wheel pinion.		88a. Barrel cover.
22. Escape-wheel pinion.		89. Fourth wheel, old.
23. Cylinder staff.		90. Third wheel, old, staked on the 3d pinion 96, old. 100
24. Barrel arbor.		91. Escape wheel, old.
25. Ratchet-wheel click.	30	92. Balance wheel (old).
30. Dial plate.		93. Balance wheel (Fig. 8).
31. Cannon pinion post.		94. Old pallet arbor and appurtenances not used in new construction. 105
32. Cannon pinion.		95. Escape cylinder (Fig. 7).
33. Hour wheel.		96. The third pinion (Fig. 3).
34. Minute wheel { compound wheel.	35	97. Second-hand gear.
35. Minute pinion }.		98. Bridge supporting the second-hand pinion 99. 110
36. Barrel, proper.		99. Second-hand pinion.
37. 2nd wheel (Fig. 2), new.		100. Post on the bridge 98.
38. Hour hand (Fig. 2).		101. The second-hand.
39. Minute hand.		102. Opening in the pillar plate, permit- ting free passage of the second-hand pinion. 115
40. Springy connecting devices holding the dial plate on the pillar plate.		103. Opening through the dial plate ac- commodating the stem of the second-hand pinion.
41. Regulator yoke.		104. Stem of the second-hand pinion.
42. Slot in the regulator yoke.		105. Staff of the center wheel 106 (Fig. 8) 120 and center pinion 86, old.
43. Clamping screw for the regulator yoke.	45	106. Center wheel (old) (Fig. 8). [Some- times called the second wheel].
44. Regulating screw.		107. Old cannon pinion (Fig. 8).
45. Screw threads of the screw 44.		108. Old minute pinion. 125
46. Circular boss of the balance cock 8.		109. Old minute wheel.
47. Teeth of regulator.	50	110. Old hour wheel.
48. Pointer on the regulator.		112. Third-wheel pinion, old.
49. Graduations on the balance cock.		113. Third wheel, old.
50. Slit in regulator 13.		114. Fourth-wheel pinion, old. 130
55. Trench in the pillar plate, accommo- dating the adjusting arm 61.		
61. Adjusting arm.		
62. Boss of the adjusting arm 61.		
63. Binding screw of balance cock 8.		
64. Dowel pins.		
66. Slot in the adjusting arm 61.		
67. Binding screw, in the slot 66.		
68. Screw for adjusting the arm 61.		
69. Jewel in the arm 61.		
70. Jewel in the balance cock 8.		
71. Regulator ring.		

115. Fourth wheel, old.

116. Escape wheel pinion, old.

117. Escape wheel, old.

It is to be understood that the parts 5 enumerated in the notation, excepting certain parts hereinafter specifically described, may be of any usual or approved construction familiar to persons skilled in the art, but the re-arrangement of the familiar parts 10 relative to each other is new, permits economy of space, and admits of the omission of numerous unnecessary parts; and the re-arranged known parts in conjunction with the new and improved parts herein described 15 constitute a very effective and dependable movement for small size watches, varying from seven lines to fourteen lines, and mark a distinct advance in the art.

Heretofore two principal types of watches 20 have been made and used, one type having a center wheel and a cylinder escapement; and the other type being without a center wheel and having a lever escapement, but to the best of our knowledge and belief, watches 25 without a center wheel and pinion and with a cylinder escapement have not been produced.

The omitting of the center wheel permits the use of a barrel of increased diameter 30 thereby increasing the leverage of the barrel and admitting of the use of a relatively light main spring, thus reducing to the minimum breakage of main springs. In small size watches it is particularly desirable to 35 use as large a barrel as possible; it is also desirable, owing to the restricted available space, to reduce as far as practicable the number of parts in the movement.

The result of the use of a relatively enlarged barrel in co-operation with a cylinder escapement, (as distinguished from the lever escapement hitherto used with the barrel), is: that the center wheel, the center pinion, 40 the pallet arbor, the pallet, two pallet stones, the fork, the pallet-bridge and the pallet-bridge screw may be dispensed with; and the strength and dependability of the small size movement as a whole will be greatly increased.

50 Gain in power.

The reduced absorption of power and the consequent gain in effectiveness, due to the diminished number of gears in our improved train, will be obvious upon comparison of Figs. 11 and 12.

In Fig. 11 there are eight gears. Assuming the power applied on the circumference of the barrel 87 to be 160 grams, it has been 60 found by experiment (see paragraphs 1068-1073 on pages 599-601, and Fig. 19 of plate XIII, of *Modern Horology in Theory and Practice*, by Claudio Saunier, (2nd ed. 1887,) that a weight of 2 grams 65 suspended from the circumference of the

gear 115 will balance a weight of 160 grams at the circumference of the gear 87; in other words

P:R::24:1920.

24:1920::1:X . . X=80.

Applying the same test to the train of six gears shown in Fig. 12 and assigning the values 16 and 12 to the respective gears 89 and 90, and the values 4 and 3 to the respective pinions 20 and 96, we have:

Product of radii of the wheels

$$16 \times 12 = 192$$

Product of radii of the pinions

$$3 \times 4 = 12$$

70

75

80

We have 12:192::1:X . . X=16

It appears then that in the train shown in Fig. 11 P:R::1:80, whereas in the train shown in Fig. 12, P:R::1:16. It is obvious 85 that there is great gain in effectiveness due to the less number of gears in our improved train shown in Fig. 12.

In small watches as hitherto constructed, the diameter of the balance is related to 90 the diameter of the cylinder approximately as 11 to 1; our improved construction admits of the use of a larger balance, the ratio being about 15 to 1 as will hereinafter appear. In small watches as hitherto constructed, there is usually a loss of about 80% 95 of power between the barrel and the escape pinion; in our improved construction, this loss is reduced approximately 50%.

In the diagram, Fig. 7, the circle 85 represents the circumference of the pillar plate; the dotted circle 86 represents the center pinion hitherto commonly used in standard watches, but not used in our improved watch; the dotted circle 87 represents the 100 circumference of the barrel commonly used in watches prior to our invention; the circle 88 represents the enlarged barrel-gear occupying more than half the diameter of the pillar plate and used in our improved construction; the circle 37 represents the second wheel of the new train; the circle 17 represents the third wheel of the new train; the circle 16 represents the escape wheel; the dotted circle 92 represents the old balance 115 wheel commonly used with a pallet arbor 94 and pinion prior to our invention, but omitted from our improved mechanism; the circle 93 represents the enlarged balance wheel used in our improved mechanism; and 120 the arc 95 represents the escape-cylinder substituted for the pallet arbor 94 and used in our improved mechanism.

125 Taking the "time" from different wheels.

In the new watch herein shown and described, the "time" is taken from the barrel-gear or first wheel. Any suitable number of teeth in the wheels, or leaves in the pinions of the train, may be used. In old construc- 130

tions the "time" is taken from the center wheel which is not used in our improved construction, and the train must be indexed to make the hour wheel revolve in one hour, and the fourth wheel revolve in one minute. In our improved watch the "time" is obtained by placing a compound-wheel, 34—35 (Fig. 9), friction tight on the cover of the barrel, and gearing this compound wheel 10 in proper ratio to revolve the hands in one hour and twelve hours respectively. The barrel is the source of power in the watch. To the best of our knowledge and belief our improved watch is the only watch using a cylinder escapement, in which the barrel directly carries the main "time" wheels which drive the cannon pinion and hour wheel.

The main train (new).

In the main train of our improved watch, what has heretofore been the center wheel is dispensed with; the wheel formerly known as the third wheel becomes the second wheel; and the former fourth wheel becomes the third wheel.

The operation of our improved main train is as follows:

(a). The barrel-gear 88 (Figs. 1 and 2) drives the 2nd pinion 20 (old 3rd).

(b). The 2nd wheel 37 staked on the 2nd pinion, drives the 3rd pinion 21, old 4th (Fig. 1).

(c). The 3rd wheel 17 (old 4th) staked on the 3rd pinion drives the escape pinion 22, and wheel 16.

(d). The escape wheel 16 staked on the escape pinion 22 transmits power of the main spring to the cylinder staff 23.

The main train (old), operation.

(a). The barrel-gear 87 (Fig. 8) drives the center pinion 86.

(b). The center wheel 106 staked on the center pinion 86 drives the 3rd pinion 96 (new 20).

(c). The third wheel 90 staked on the 3rd pinion 96 drives the 4th pinion 21 (Fig. 1).

(d). The 4th wheel 89 (new 17) staked on the 4th pinion 21 drives the escape pinion 22 and wheel 91.

(e). The escape wheel 91 (new 16) staked on the escape pinion 22 transmits the power of the main spring (not shown) to the cylinder staff 23.

The dial train (new).

The dial train (Figs. 2 and 9) of our improved watch comprises the barrel-gear 88; the main compound drive wheel and pinion which includes the minute wheel 34 and the minute pinion 35 and which drives the cannon pinion 32 and hour wheel 33; as distinguished from the old dial train which derives its power from the cannon pinion.

In the new system the hands are driven directly from the barrel, the source of power, thereby obtaining greatly increased power. In old constructions the cannon pinion fits friction-tight on the staff 105 (Fig. 8) of the center wheel 106 and the center pinion 86; and the cannon pinion 107 staked on the same staff drives the entire dial train.

The operation of our improved dial train is as follows;

(a). The barrel-gear 88 carries the main drive or minute wheel 34 and the integral minute pinion 35. The main drive compound wheel 34—35 has a friction connection with the barrel cover 88^a and drives the cannon pinion 32.

(b). The main drive pinion 35, integral with the main drive wheel 34, drives the hour wheel 33. The minute hand 39 rotates with the cannon pinion 32; and the hour hand 38 rotates with the hour wheel 33.

The dial train (old), operation.

(a). The barrel-gear 87 (Fig. 8) drives the center pinion 86.

(b). The cannon pinion 107 has friction connection with the staff 105 of the center pinion 86 (instead of with the cover 88^a of the barrel 36, as in the new construction).

(c). The cannon pinion 107 drives the minute wheel 109. The minute hand rotates with the cannon pinion 107.

(d). The minute pinion 108 staked in the minute wheel 109 drives the hour wheel 110, and the hour hand rotates with the hour wheel.

The enlarged balance wheel.

It is found in practice that small size watches as hitherto constructed are subject to frequent stoppages by slight shocks and are unreliable by reason of the fact that the balance, being disproportionately small, has feeble inertia and on that account is ineffective to maintain continuous operation of the escapement.

Experiment has determined that in standard watches the diameter of the theoretically perfect balance is to the diameter of the cylinder as 16 is to 1; but in small size watches this ratio has not hitherto been even approximately attained.

In small size watches, (say 10 $\frac{1}{2}$ lines) as hitherto constructed, the ratio of the balance to the cylinder is as 11 to 1, whereas in our improved construction, the ratio of the balance to the cylinder—in the same size watch—is as 15 to 1. The very limited space available in small size watches, as hitherto constructed, does not admit of the use of the enlarged balance wheel which is used in our improved construction.

To illustrate the advantage gained by our improved construction, let D represent the

diameter of the cylinder used in a $10\frac{1}{2}$ line watch as hitherto constructed, and also the diameter of the cylinder used in our improved watch of the same size. By measurement it is found that $11 D$ will be the diameter of the balance hitherto used; whereas $11 D + 4 D = 15 DD$, will be the diameter of the enlarged balance used in our improved construction, showing a gain of $4/11$ ths, or 36.36% in the diameter of the balance. Referring to Fig. 7 it will appear that the increased diameter of the balance wheel used in our improved construction is attained by reason of the fact that the pallet arbor 94 and appurtenances being dispensed with and the cylinder escapement 95 substituted, the center of the escape-cylinder may be much nearer to the circumference of the escape wheel than is possible with a lever escapement, and the cylinder being co-axial with the balance wheel 93, the diameter of the balance wheel may be increased to such extent that the diameter of the barrel 88 plus the diameter of the balance wheel 93 will extend practically the entire diameter of the pillar plate 85. It is obvious that our improved construction allows space for a balance wheel of much greater diameter than has hitherto been used in small size watches.

The inertia of the balance wheels—mass and other things being equal—will vary as the squares of their diameters. In the present instance, taking 15 and 11 as the values of the respective diameters, we have: 15^2 squared minus 11^2 squared = $225 - 121 = 104$ difference of inertia; representing a gain of 85.95% in efficiency by reason of the increased inertia of the balance wheel of increased diameter.

Here it is to be noted that, in our improved construction, the ratio (15 to 1) of the balance wheel to the cylinder, is a very close approximation to the ideal ratio, 16 to 1.

The cylinder-staff adjuster.

To attain accurate adjustment of the cylinder-staff relative to the escape wheel with which it co-operates, we provide means, (Figs. 5 and 6), which will now be described. Suitably located in the pillar plate 1 are; a cylinder-staff-opening 72 in line with the cylinder-staff 23, a trench 60 in which the adjusting arm 61 is oscillative, and a circular boss-opening 73 in which the circular boss 62 of the arm is fitted so that the boss will rotate accurately in the opening.

The balance cock 8 has holes 74, matching dowel pins 64 on the boss and a hole 73 accommodating a screw 63 which screws into the boss and clamps the balance cock on the boss. The arm 61 has an arcuate slot 66. A screw 67 extends through the slot and screws into the pillar plate to clamp the arm on the

plate. The slot 66 is of suitable length to permit transverse movement of the arm within the scope of the trench 60. A jewel 69 at the free end of the arm is in line with a jewel 70 near the outer end of the balance cock, and the pivots of the cylinder-staff bear in the respective jewels. An adjusting screw 68 screws into the pillar plate and its inner end engages on the edge of the arm 61, and by turning the screw inwardly, or outwardly, as the case may be, very accurate adjustment of the arm may be made. Upon loosening the screw 67, the arm 61 may be turned to the right or to the left to adjust the cylinder-staff in proper relation to the escape wheel; and when the staff is properly adjusted, the screw 67 will be tightened to keep the parts in their adjusted position.

The removable dial plate.

A defect common to watches as constructed prior to our invention is, that in repairing the watch it is necessary to remove the hands before the dial can be taken off, and the hands being very small and fragile, are very likely to be lost or broken. To overcome this defect, we have devised a construction such that the dial plate may be removed and replaced without previously removing the hands. The improved construction is clearly shown in Figs. 2 and 3.

The circular dial plate 30 rests on, and is conformed to the outer surface of the pillar plate 1, and has a central opening 78 accommodating the elongated hub 77 of the hour wheel 33.

In the pillar plate is a trench 76 accommodating the hour wheel 33, the minute pinion 35, the minute wheel 34, and the cannon pinion 32. The vertical cannon pinion post 31 is stationary on the pillar plate and the cannon pinion is rotative on the post. The hour wheel 33 has an elongated hub 77 surrounding the elongated hub 79 of the cannon pinion and extended outwardly through the hole 78 and beyond the outer face of the hub.

The minute hand 39 is fixed on and rotates with the hub 79, and the hour hand 38 is fixed on and rotates with the hub 77. The cannon pinion 32 is actuated by the minute wheel 34, and the hour wheel 33 is actuated by the minute pinion 35. Upon removing the dial plate from the pillar plate, the pinion 32 will be disengaged from the wheel 34, the wheel 33 will be disengaged from the pinion 35; and the pinion 32, the wheel 33 and the hands 38 and 39 will go with the dial plate.

The second hand and its gears are shown in Fig. 3 in proper relation to the detachable dial plate and will now be described.

The third wheel 90, the third pinion 96, and the second-hand gear 97 are of usual construction but are used in a new relation to other parts. A bridge 98 is stationary on the

6
pillar plate 1. A post 100 is stationary on the bridge. The second hand pinion 99 rotative on the post 100 has a stem 104 and is actuated by the gear 97. In the pillar plate 5 is a second-hand pinion-opening 102 to permit free passage of the pinion 99 through the opening. In the dial plate is an opening 103, in line with the opening, 102, and adapted to permit free rotation of the stem 104. 10 The second hand 101 is fixed on the stem 104. Detaching of the dial plate will cause disengagement of the pinion 99 from the gear 97 and the removal of the pinion from the post 100; and the pinion 99 and the second hand 15 101 will go with the dial plate.

The pillar plate 1 preferably has a circumferential rim 80 provided with suitably placed notches 81.

The circular dial plate 30 (Fig. 10) is of 20 thin springy metal and has a central opening 78 and integral L-shape snap-members spaced apart from each other according to the spacing of the notches 81 in the rim 80. In practice, the dial plate and the snap-members, each comprising a finger 40, and a neck 83, will be pressed from the metal sheet and will be bent along the lines 82 to set the members at right angles to the plate, at one 25 operation. Characters designating the hours and minutes may be applied on the face of the dial plate by any usual or approved method. To connect the dial plate with the pillar plate, the dial plate will be placed on the pillar plate with the necks 83 in line with 30 the respective notches 81 of the pillar plate and the dial plate will be pressed downward to cause the necks to enter the notches and cause the fingers 40 to engage the under side of the rim 80. To disconnect the dial plate 35 19 this procedure will be reversed.

While we have shown and prefer to use a notched pillar plate and a dial plate having snaps adapted to engage in the notches of the pillar plate, it is to be understood that our 40 invention includes broadly a pillar plate adapted to take on a dial plate and any dial plate adapted to snap onto the pillar plate.

The regulator.

50 The regulator, designated as a whole by the numeral 13, is mounted as is usual, on the balance cock 8. The balance cock has a circular boss 46, the outer circumference of which is of tapered cross-section. The boss 55 has on its outer face a series of graduations 49. The regulator ring 71 has a radial arm 18 provided with regulator pins 19, between which the outside coil of the hair spring 15 is situated in the usual manner; it also has a 60 radial slit 50, teeth 47 occupying an arc of the ring, and a pointer 48. The inner circle of the ring is tapered inversely to the tapered member of the boss. The slit 50 permits slight spreading of the ring so that it 65 may be pressed onto the boss and the parts

are fitted so that when the ring is in place, it may be rotated on the boss.

A yoke 41, situated on the face of the balance cock, has a slot 42 accommodating a clamping screw 43 which connects the yoke 70 with the balance cock so that the yoke may be adjusted relative to the regulator ring. A screw 44 rotative in bearings on the yoke has screw threads 45 which engage the teeth 47 of the ring to rotate the ring more or less, 75 in either direction. Inasmuch as one complete rotation of the screw is necessary to rotate the ring to the extent of one tooth, the device admits of very accurate movement of the ring, the scope of the movement being indicated by the position of the pointer 48 relative to the graduations 49.

We have shown and described preferable details of construction, but it is obvious that minor details may be varied and still be 85 within the scope of our invention; we therefore do not restrict the claims to the precise details of construction herein disclosed.

What we claim as new, and desire to secure by Letters Patent is:

90 1. In a watch, a pillar plate of predetermined diameter and a barrel having a diameter greater than half the diameter of the pillar plate; in combination with a balance wheel having a diameter somewhat less than half the diameter of the pillar plate; an escape-cylinder co-axial with the balance wheel and of a diameter related to the diameter of the balance wheel approximately as 1 to 15, and an escape wheel co-acting 95 with the escape-cylinder.

2. In a watch, a pillar plate of predetermined diameter and a barrel having a diameter greater than half the diameter of the pillar plate; in combination with, a second 105 pinion, a second wheel, a third pinion, a third wheel, an escape wheel pinion, an escape wheel, an escape-cylinder, and a balance wheel.

3. In a watch of the class described, the 110 combination of a pillar plate of predetermined diameter; a barrel and a balance wheel extending practically the entire diameter of the pillar plate; an escape-cylinder co-axial with the balance wheel and of a 115 diameter related to the diameter of the balance wheel approximately as 1 to 15; and an escape wheel co-acting with the escape cylinder.

4. In a watch of the class described, the 120 train comprising, a barrel, a second pinion, a second wheel, and a third pinion; in combination with a cylinder escapement.

5. In a watch of the class described, the 125 train comprising a barrel, a second pinion, a second wheel, a third pinion, a third wheel and an escape pinion; in combination with an escape-cylinder, a balance wheel co-axial with the escape-cylinder and of a diameter related to the diameter of the escape-cylinder- 130

der approximately as 15 to 1; and an escape wheel co-acting with the escape-cylinder.

6. In a watch, the combination of a barrel and its gear, a compound gear comprising a 5 minute wheel and a minute pinion mounted on and having frictional connection with the barrel; a cannon pinion and an hour wheel driven by said compound gear; and a cylinder escapement controlling the action of the 10 gears.

7. In a watch, a barrel carrying the main time gears; in combination with a cannon pinion and an hour wheel actuated directly by the main time gears; and a cylinder escapement and balance wheel controlling the 15 action of the gears.

8. In a watch, the combination of a main train; a barrel having a barrel gear directly actuating the main train; a dial train directly actuated by a compound gear on the 20 barrel; and a cylinder escapement controlling the action of both trains.

9. In a watch, the combination of a pillar plate; a top plate; a main spring; a barrel; 25 and a second wheel, a second pinion, a third wheel, a third wheel pinion, an escape-wheel

and an escape wheel pinion, between the pillar plate and the top plate.

10. In a watch, the combination of a pillar plate, a top plate, and a main train between the pillar plate and the top plate and comprising four wheels and three pinions co-acting with a cylinder escapement. 30

11. In a watch, a main train, admitting a variable number of teeth on the wheels and 35 variable numbers of leaves on the pinions according to the size of the watch; and a time train independent of the main train and adapted to be suitably geared to co-act with wheels of the main train having variable numbers of teeth, and pinions of the main train having variable numbers of leaves. 40

In witness whereof we have signed our names at Springfield, Illinois, this 17th day 45 of May, 1919.

FRED R. COATS.
JEAN F. HARTWELL.

Witnesses:

J. S. THOMPSON,
N. DU BOIS.
